BAG DELIVERY MECHANISM FOR BAG CLOSING MACHINES

Harold V. Kindseth and Frank L. Hopkins, Minneapolis, Minn., assignors to Bemis Bro. Bag Co., Minneapolis, Minn., a corporation of Missouri

Application December 5, 1951, Serial No. 259,994

9 Claims. (Cl. 198—110)

1

Our invention relates generally to improvements in bag closing machines and more particularly to mechanism for handling filled bags after closing and sealing thereof.

More specifically, our invention is in the nature of an improvement on certain of the structures disclosed in the United States Letters Patent No. 1,868,686 and No. 1,989,471, granted to Daniel Belcher.

In bag closing and sealing machines of the character exemplified in the United States patents above identified, the filled bags are generally supported and held in rotary bag-holding devices during the closing and sealing of the bags, after which the sealed bags are deposited on conveyors for transport to points remote from the bag-holding devices.

In the machine of the present invention, the closed and sealed bags are received from the bag-holding device by a conveyor which delivers the sealed bags to a second conveyor which, in turn, carries the bags at a predetermined speed away from the machine to a suitable place for packing the bags in cartons or otherwise disposing of the same. The speed of conveying movement of the second conveyor is preferably less than the normal speed of the first conveyor for the purpose of allowing sufficient time for the adhesive used in sealing the bags to become dry, or at least set, before further handling. The normal speed of the first conveyor for the sealed bag is sufficient to move the bags out of reach of the moving bag holder once the bag is delivered thereto, in order to prevent the filled bag from being jostled or tipped by the bag-holding device during its continued movement. When the bag approaches the station at which it is transferred to the second conveyor, the difference between the normal speed of the first conveyor and that of the second conveyor is often sufficient to cause the bag to upset when the same is transferred to the second conveyor. An important object of our invention is, therefore, the provision of means for moving the first conveyor at a given speed when the conveyor receives a closed and sealed bag from the bag-holding device and at a different speed when the sealed bag approaches the station where it is transferred to the second conveyor.

Another object of our invention is the provision of novel speed change mechanism and automatic control means therefor, said control means being operative to cause changes in output speed of the speed change mechanism.

Another object of our invention is the provision

5 of a delivery conveyor and operating mechanism therefor, in machines of this character, which is relatively simple and inexpensive to produce, which is efficient in operation, and which is rugged in construction and durable in use.

Other highly important objects and advantages of our invention will become apparent from the following detailed specification, appended claims, and attached drawings.

10 Referring to the drawings which illustrate the invention and in which like characters indicate like parts throughout the several views:

Fig. 1 is a view in side elevation of a closing and sealing mechanism for filled bags incorporating our invention;

15 Fig. 2 is an enlarged fragmentary view in side elevation of certain operating elements of the machine of our invention, some parts being broken away and some parts shown in section;

Fig. 3 is a top plan view of a portion of the delivery mechanism of the machine illustrated in Figs. 1 and 2;

20 Fig. 4 is a fragmentary view in side elevation of the delivery mechanism of our invention, some parts being broken away;

Fig. 5 is an enlarged fragmentary view in side elevation of the speed change mechanism of our invention;

25 Fig. 6 is an axial section taken substantially on the line 6—6 of Fig. 5;

Fig. 7 is a fragmentary view in plan and partly in section taken substantially on the line 7—7 of Fig. 6;

30 Fig. 8 is a detail in section, taken substantially on the line 8—8 of Fig. 6; and

Fig. 9 is a transverse section taken on the line 9—9 of Fig. 6 on a slightly reduced scale.

35 Referring with greater detail to the drawings, a frame structure 1 is shown as supporting a conveyor mechanism 2 which may be assumed to be of the endless belt variety and which comprises a portion of means for delivering open-topped filled movable bags 3 to a movable bag-holding member indicated in its entirety by the numeral 4. The said movable member includes a disc-like rotor 5 having mounted thereon a plurality of circumferentially spaced plate-like side wall forming members 6 which cooperate therewith to form bag-holding compartments 7 each

40 containing one of the bags 3. The compartments 7 are further defined by stationary end wall forming elements 8 and movable wall elements 9, see Fig. 2. The movable element 4 is journaled for rotation on a shaft 10 which extends transversely 45 of the frame 1 and is secured at its opposite ends

therein. With further reference to Fig. 2, it will be seen that the stationary cam 11 engages a plurality of cam follower rollers 12 one each associated with one of the plate-like compartment walls 6 whereby said walls 6 are movable laterally to clamp and release a bag therebetween and the opposite side wall formed by the rotor 5. Coil tension springs 13 bias the cam followers 12 toward engagement with the cam 11.

The movable member 5 has mounted fast thereon a gear 14 which has meshing engagement with a pinion 15 fast on a drive shaft 16 journaled in suitable bearings 17 in the frame 1, one of said bearings being shown in Fig. 6. The drive shaft 16 is driven from a suitable source of power such as an electric motor 18 through suitable transmission mechanism such as an endless drive belt 19 running over suitable pulleys 20 and 21 one on the shaft of the motor 18 and the other on the input shaft of a conventional speed reducer 22. A second endless drive belt or chain 23 may be assumed to run over suitable pulleys or sprockets, not shown but mounted one each on the output shaft of the speed reducer 22 and the drive shaft 16.

When each bag 3 is delivered to a compartment 7 in the movable member 4, continued rotation of the movable member 4 will place the bag in position wherein suitable adhesive is applied to the upper end thereof, said upper end being then folded to a closed and sealed position. One of the top-folding mechanisms is shown in Fig. 1 and is indicated in its entirety at 24. As the movable member 4 rotates, the closed tops of the bags are successively brought into engagement with an arcuate plate-like stationary member 25, see Fig. 2, which maintains the tops in a closed position during the latter part of travel of the bag about the axis of the movable member 4.

As each bag 3 passes beyond the trailing edge of the plate 25 under rotation of the movable member 4, the side wall forming plate 6 of the compartment 7 in which the bag is contained is permitted to move laterally outwardly, thus releasing the bag 3 which engages a platform 26 that is pivotally mounted on the outer ends of a pair of parallel arms 27, the inner ends of which are pivotally secured to a bracket 28 mounted on the frame 1. A coil tension spring 29 biases the platform 26 in a generally upstanding direction toward the rotary member 4. However, the weight of a filled bag 3 is sufficient to overcome the bias exerted by the spring 29 and, when the filled bag 3 engages the platform 26, said platform lowers to deposit the bag 3 gently on the upper operative flight 30 of an endless belt conveyor 31. It should here be noted that the arcuate pressure plate 25 is mounted on the upper end of the bracket 28 by a suitable mounting element 25', and that the platform 26 maintains the freshly pasted bag sealed until the bag is deposited on the conveyor 31.

The above-described elements comprise a bag closing and sealing machine which is more fully disclosed in the United States patents to Belcher, above identified, and a co-pending application for United States patent filed December 1, 1950, by Harold V. Kindseth, Serial No. 198,663, and entitled "Bag Supporting Means for Bag Closing and Sealing Machines," and now Patent No. 2,599,893. In view of the above disclosures, it is not deemed necessary to describe the foregoing in greater detail herein.

The endless conveyor belt 31 runs over a pair of pulleys 32 and 33 mounted on shafts 34 and

35 respectively that are journaled in suitable bearing brackets 36 and 37 on the frame structure 1. A portion of the belt 31 underlies the rotary member 4 so as to receive a filled bag 3 therefrom, in an inverted position. The bags 3 are supported in an upright position, when directed to the conveyor 31, by a pair of laterally spaced upstanding guide plates or the like 38 and laterally spaced pairs of guide belts 39 and 40 each running over pulleys 41 and 42 fast on shafts 43 and 44 respectively journaled in suitable bearings 45 and 46 respectively carried by the frame structure 1. The guide belts 39 and 40 of each pair thereof are driven from the shaft 34 of the conveyor belt pulley 32 by means of an endless link chain 47 running over a sprocket wheel 48 fast on the shaft 34 and another sprocket wheel 49 mounted fast on a shaft 50 which is suitably journaled in a bearing bracket 51 and an endless belt 52 running over a pulley 53 fast on the shaft 50 and another pulley 54 mounted fast on the shaft 44 at right angles to the shaft 50. With reference to Fig. 3, it will be seen that each of the pairs of guide belts 39 and 40 are independently driven from the shaft 34 by identical chains and belts 47 and 52 respectively.

The inverted, closed, and sealed bags 3 are directed by the delivery conveyor 31 at a point or station remote from the movable member 4 to a second delivery conveyor 55. The conveyor 55 may be of any suitable type, but preferably and as shown, is of the conventional endless belt variety comprising a supporting frame 56 and an endless belt 57 running over suitable spaced pulleys or the like 58, one of which is shown. The conveyor belt 57 delivers the bags to a suitable point where the bags are packed in cartons or otherwise prepared for storage or shipment, and is driven at a considerably lower speed than the normal speed of the first delivery conveyor belt 31. When a closed and sealed bag is deposited onto the upper flight 30 of the conveyor belt 31 from its compartment 7, the bag must be moved by the conveyor 31 at a rate of speed sufficient to avoid its being upset by any projecting part of the constantly rotating movable member 4 such as for instance the adjacent compartment end wall member 8. For this reason, the normal speed of the conveyor belt 31 should be at least as great or greater than the peripheral speed of the movable member 4. However, when the bag 3 approaches the station at which it is transferred to the conveyor belt 57, its speed should be retarded to approximately the speed of travel of the belt 57 so that there is no danger of upsetting the bag at this point. To accomplish this end, we provide automatic speed change mechanism for driving the first conveyor belt 31 at relatively high speed when a bag 3 is deposited thereon from the movable member 4 and at a relatively low speed when the bag 3 approaches the second conveyor 55, said mechanism now to be described.

With reference particularly to Fig. 6, it will be seen that the one end of the drive shaft 16 projects outwardly from the frame structure 1 and has keyed or otherwise rigidly secured thereto mounting means in the nature of a flange 59. Journaled on the shaft 16 for rotation relative thereto is a sleeve 60 which is formed at its inner end adjacent the flange 59 to provide a driven element in the nature of a pinion or sun gear 61. A drive wheel or sprocket 62 is telescoped over the outer end portion of the sleeve 60 and has locked thereto for common rotary

movement a key or the like 63. The sprocket 62 is provided with an axially outwardly projecting hub 64 which at its outer end is formed to provide a recess 65 for the reception of a conventional overrunning clutch 66. The clutch 66 comprises an inner member 67, a cooperating outer member 68, and a plurality of rollers or the like 69 which engage outer and inner surfaces of the members 67 and 68 respectively. The inner member 67 is keyed to the outer reduced end 70 of the drive shaft 16, as indicated at 71, and held against axial movement by a washer 72 and a lock washer-equipped nut 73 screw-threaded on the reduced end 70 of the shaft 16. The outer member 68 engages the side wall of the recess 65 with a press fit to be rotatable therewith. Obviously, with this arrangement, the drive shaft 16 is operative to rotate the sprocket wheel 62 but permits "free wheeling" of the sprocket wheel 62 at speeds greater than the speed of rotation of the shaft 16 in the same direction for a purpose which will hereinafter become apparent. A flanged collar 74 is journalled on the sleeve 60 intermediate the sun gear 61 and the sprocket wheel 62 by means of anti-friction bearings 75 and has anchored to its outer peripheral portion, by means of bolts or the like 76, a driven element in the nature of a ring gear 77 concentric with the sun gear 61. A plurality, as shown 3, of planet gears 78 are journalled for rotation on circumferentially spaced stub shafts 79 and have intermeshing engagement with the sun gear 61 and the ring gear 77. The stub shafts 79 are rigidly secured to the flange 59 by means of lock washer-equipped nuts or the like 80, one of which is shown.

The mechanism immediately above described is one form of an epicyclic train which, for the purpose of the present example, comprises what is known as a type of planetary transmission. With the arrangement shown, if the collar 74 and ring gear 77 are permitted to rotate freely, the sleeve 60 will tend to rotate at the same speed as that of the shaft 16. However, any load placed upon the sprocket wheel 62 will tend to reduce the speed of the sleeve 60 whereupon the sprocket wheel 62 will be driven by the drive shaft 16 through the overrunning clutch 66. It should here be noted that the sprocket wheel 62 forms the driver for the first delivery conveyor 31 and is connected thereto by driving connections including an endless link chain or belt 81 running over said sprocket wheel 62 and one of a pair of connected idler sprockets 82 journalled on a stub shaft 83 secured to the frame structure 1, and a second endless link chain or belt 84 running over the other of said pair of sprockets 82 and a driven sprocket 85 keyed or otherwise anchored to the shaft 34 of the first delivery conveyor.

If, at any time during rotation of the shaft 16 and the parts carried thereby, the collar 74 and ring gear 77 carried thereby should be locked against rotation, rotary movement of the flange 59 will be transferred through the planet gears 78 to the sun gear 61 and sleeve 60 at a greater speed than that of the shaft 16. Consequently, the drive wheel sprocket 62 together with the first delivery conveyor 31 will be driven at a greater speed than formerly. Means for periodically locking the collar 74 and ring gear 77 against rotary movement for predetermined intervals and releasing the same for rotation comprises a pair of diametrically opposed abutments 86 and 87 extending radially outwardly from the

periphery of the collar 74, a stop element 88, and a cam 89 for moving the stop element 88 out of the path of travel of the abutment members 86 and 87 and permitting return thereof into the path of travel of said abutments at predetermined intervals. The stop element 88 is in the nature of a head on one end portion of a slide rod 90 carried by a rock arm 91 pivotally mounted to the frame structure 1, as indicated at 92. A guide bracket 93 has an inturned portion 94 at its outer end, see Fig. 7, which forms the base of reaction for one of a pair of cushioning springs 95 which engage adjustable collars 96 on the slide rod 90 and cushion the impact of the abutments 86 and 87 against the stop element or head 88. The free end of the rock arm 91 is provided with a bearing boss 97 which supports a cam follower roller 98 that lies in the plane of the cam 89 and engages the same. Said cam 89 is formed to provide a relatively short circumferentially extended stop element releasing portion 99 and a relatively long circumferentially extended portion 100 which, when engaged by the cam follower roller 98 permits the stop element 88 to enter the path of travel of the abutments 86 and 87. We further provide yielding means in the nature of a coil tension spring 101 anchored at one end to a crank-acting portion 102 integrally formed with the rock arm 91 and at its other end to the frame 1, as indicated at 103, see Fig. 1. The cam 89 is rigidly secured to the flange 59 by circumferentially spaced bolts 104, one of which is shown, see Fig. 6. The bolts 104 are provided with clamping washers 105 and permit adjustment of the cam 89 circumferentially with respect to the drive shaft 16.

The high portion 99 of the cam 89 is so positioned on the flange 59 so that when a closed and sealed bag 3 is being deposited on the operative flight 30 of the first conveyor belt 31, the stop element or head 88 is positioned to engage one of the abutments 86-87. As above indicated, this engagement will cause the conveyor belt 31 to run at its normal relatively high speed as the bag 3 is deposited thereon. Preferably, the arrangement is such that the speed of linear travel of the conveyor belt 31 is approximately one-fourth greater than the peripheral speed of the rotary member 4. Hence, the bag 3 is quickly moved out of the path of travel of any portion of the rotary member which might otherwise come into contact with and upset the same. As the bag approaches the end of the operative flight at which point it will be transferred to the relatively slow conveyor belt 57, the high portion 99 of the cam 89 engages the cam follower roller 98, moving the stop element 88 out of engagement with the adjacent abutment. This action permits rotary movement of the collar 74 and the ring gear 77 and causes the sprocket wheel 62 to be driven through the overrunning clutch 66 at relatively low speed, said low speed being approximately that of the second conveyor belt 57. As soon as the cam 89 permits return of the stop element 88 into the path of travel of one of the abutments 86 and 87, under bias of the spring 101, the resultant engagement of one of the abutments with the stop element will again cause the drive wheel or sprocket 62 to be driven through the sun gear 61 at relatively high speed to convey the next bag 3 away from the movable or rotary member 4. The slow movement of the second conveyor provides ample time for the adhesive used in sealing the bags to set while the bags are in an inverted position thereon. In the event that a relatively

quick drying adhesive is used and that the second conveyor belt 57 is operated at a greater speed, the spring 101 can be disconnected from the lever arm 102, thus permitting the rock arm 91 to swing under the action of gravity to a point where the stop element 88 is permanently removed from the path of travel of the abutments 86 and 87. However, the downward swinging movement of the rock arm 91, under the action of gravity, will move the extreme upper end 102' of the crank-acting portion 102 into the path of travel of the abutments and, upon engagement thereof, will place the epicyclic train in condition to drive the conveyor belt 31 at constant high speed unaffected by rotation of the cam 89.

Our invention has been thoroughly tested and found to be completely satisfactory for the accomplishment of the objectives set forth; and, while we have shown and described a preferred embodiment of our novel mechanism, it will be understood that the same is capable of modification as to structure and arrangement of parts without departure from the spirit and scope of the invention, as defined in the claims.

What we claim is:

1. Automatic speed change transmission mechanism for delivery conveyors or the like, said mechanism comprising a frame, a power driven shaft journalled for rotation in said frame, a drive wheel, overrunning clutch means coupling the drive wheel to said shaft, an epicyclic train including a driving gear carried by the drive shaft and a pair of driven gears in meshing engagement with said driving gear, one of said driven gears being secured to the drive wheel for common rotation therewith, the other of said driven gears being rotatable on the axis of said drive shaft, and mechanism for periodically locking said other driven gear against rotation for predetermined intervals and releasing the same, whereby the drive wheel is rotated by said one of the drive gears when said other driven gear is locked against rotation, said drive wheel being driven by the drive shaft through said overrunning clutch means responsive to release of said other driven gear, said locking and releasing mechanism comprising an abutment carried by said other driven gear, a stop element mounted on the frame for movements into and out of the path of travel of said abutment and biased toward engagement therewith, and mechanism responsive to rotation of the drive shaft to move said stop element out of the path of travel of said abutment against said bias during predetermined rotary movement of the drive shaft and to permit movement of the stop element into the path of travel of said abutment during other predetermined rotary movement of the drive shaft.

2. Automatic speed change transmission mechanism for delivery conveyors or the like, said mechanism comprising a frame, a power driven shaft journalled for rotation in said frame, a drive wheel, overrunning clutch means coupling the drive wheel to said shaft, an epicyclic train including a driving gear carried by the drive shaft and a pair of driven gears in meshing engagement with said driving gear, one of said driven gears being secured to the drive wheel for common rotation therewith, the other of said driven gears being rotatable on the axis of said drive shaft, and mechanism for periodically locking said other driven gear against rotation for predetermined intervals and releasing the same, whereby the drive wheel is rotated by said one of the driven gears when said other driven gear

is locked against rotation, said drive wheel being driven by the drive shaft through said overrunning clutch means responsive to release of said other driven gear, said locking and releasing mechanism comprising an abutment carried by said other driven gear, a stop element mounted on the frame for movements into and out of the path of travel of said abutment and biased toward engagement therewith, and cam means mounted for common movement with the driving gear on the drive shaft and operative to move said stop element out of the path of travel of said abutment against said bias during predetermined rotary movement of the drive shaft and permitting movement of the stop element into the path of travel of said abutment during other predetermined rotary movement of the drive shaft.

3. Automatic speed change transmission mechanism for delivery conveyors or the like, said mechanism comprising a frame, a power driven shaft journalled for rotation in said frame, a drive wheel, overrunning clutch means coupling the drive wheel to said shaft, an epicyclic train including a driving gear carried by the drive shaft and a pair of driven gears in meshing engagement with said driving gear, one of said driven gears being secured to the drive wheel for common rotation therewith, the other of said driven gears being rotatable on the axis of said drive shaft, and mechanism for periodically locking said other driven gear against rotation for predetermined intervals and releasing the same, whereby the drive wheel is rotated by said one of the drive gears when said other driven gear is locked against rotation, said drive wheel being driven by the drive shaft through said overrunning clutch means responsive to release of said other driven gears, said locking and releasing mechanism comprising an abutment carried by said other driven gear, a stop element means mounting the stop element on said frame for movements into and out of the path of travel of said abutment, yielding means biasing the stop element toward said path of travel of the abutment, and mechanism responsive to rotation of the drive shaft to move said stop element out of the path of travel of the abutment during predetermined rotary movement of the drive shaft and to permit the bias of said yielding means to move the stop element into the path of travel of said abutment during other predetermined rotary movement of the drive shaft.

4. The structure defined in claim 3 in which said last-mentioned mechanism comprises a cam carried by the drive shaft for common rotary movement therewith and a cooperating cam follower carried by the mounting means for said stop element.

5. In a machine for closing and sealing filled bags, a movable member having therein a compartment for holding a filled bag during the closing and sealing thereof, a conveyor for the reception of a closed and sealed bag from said compartment and delivery of said bag to a station remote therefrom, means for imparting operative movements to said movable member and including a drive shaft, and means coupled to said drive shaft for imparting delivery movements to said conveyor at a given speed when receiving a bag from the movable member and at a different speed when the bag approaches said station, said last-mentioned means comprising a drive wheel, overrunning clutch means coupling the drive wheel to the drive shaft, driving connections between the drive wheel and

the conveyor, and an epicyclic train including a driving gear carried by the drive shaft and a pair of driven gears in meshing engagement with the driving gear, one of said driven gears being secured to the drive wheel for common rotation therewith, the other of said driven gears being rotatable on the axis of said drive shaft, and mechanism for periodically locking said other driven gear against rotation for predetermined intervals and releasing the same, whereby the drive wheel is rotated by said one of the driven gears when said other driven gear is locked against rotation said drive wheel being driven by the drive shaft through said overrunning clutch means responsive to release of said other driven gear, said locking and releasing mechanism comprising an abutment carried by said other driven gear, a stop element mounted on the frame for movements into and out of the path of travel of said abutment and biased toward engagement therewith, and mechanism responsive to rotation of the drive shaft to move said stop element out of the path of travel of said abutment against said bias during predetermined rotary movement of the drive shaft and to permit movement of the stop element into the path of travel of said abutment during other predetermined rotary movement of the drive shaft.

6. In a machine for closing and sealing filled bags, a movable member having therein a compartment for holding a filled bag during the closing and sealing thereof, a conveyor for the reception of a closed and sealed bag from said compartment and delivery of said bag to a station remote therefrom, means for imparting operative movements to said movable member and including a drive shaft, and means coupled to said drive shaft for imparting delivery movements to said conveyor at a given speed when receiving a bag from the movable member and at a different speed when the bag approaches said station, said last-mentioned means comprising a drive wheel, overrunning clutch means coupling the drive wheel to the drive shaft, driving connections between the drive wheel and the conveyor, and an epicyclic train including a driving gear carried by the drive shaft and a pair of driven gears in meshing engagement with the driving gear, one of said driven gears being secured to the drive wheel for common rotation therewith, the other of said driven gears being rotatable on the axis of said drive shaft, and mechanism for periodically locking said other driven gear against rotation for predetermined intervals and releasing the same, whereby the drive wheel is rotated by said one of the driven gears when said other driven gear is locked against rotation, said drive wheel being driven by the drive shaft through said overrunning clutch means responsive to release of said other driven gear, said locking and releasing mechanism comprising an abutment carried by said other driven gear, a stop element, means mounting the stop element for movements into and out of the path of travel of said abutment, yielding means biasing the stop element toward said path of travel of the abutment, and mechanism responsive to rotation of the drive shaft to move said stop element out of the path of travel of the abutment during predetermined rotary movement of the drive shaft and to permit the bias of said yielding means to move the stop element into the path of travel of the abutment during other predetermined rotary movement of the drive shaft.

7. The structure defined in claim 6 in which said last-mentioned mechanism comprises a cam carried by the drive shaft for common rotary movement therewith and a cooperating cam follower carried by the mounting means for said stop element.

8. In a machine for closing and sealing filled bags, a movable member having therein a compartment for holding a filled bag during the closing and sealing thereof, a conveyor for the reception of a closed and sealed bag from said compartment and delivery of said bag to a station remote therefrom, means for imparting operative movements to said movable member and including a drive shaft, and means coupled to said drive shaft for imparting delivery movements to said conveyor at a given speed when receiving a bag from the movable member and at a different speed when the bag approaches said station, said last-mentioned means comprising a drive wheel, overrunning clutch means coupling the drive wheel to the drive shaft, driving connections between the drive wheel and the conveyor, an epicyclic train including a driving gear carried by the drive shaft and a pair of driven gears in meshing engagement with said driving gear, one of said driven gears being secured to the drive wheel, the other of said driven gears being rotatable on the axis of said drive shaft, and mechanism for periodically locking said other driven gear against rotation for predetermined intervals, whereby the drive wheel is rotated by said one of the driven gears, said drive wheel being driven by the drive shaft through said overrunning clutch means responsive to release of said other driven gear for free rotation, said last-mentioned mechanism comprising an abutment carried by said other gear, a stop element movable into and out of the path of travel of said abutment and biased toward engagement therewith, and cam means mounted for common movement with said driving gear on the drive shaft and operative to move said stop element out of the path of travel of said abutment against said bias during predetermined rotary movement of the drive shaft and permitting movement of the stop element into the path of travel of said abutment during other predetermined rotary movement of the drive shaft.

9. Automatic speed change transmission mechanism for delivery conveyors or the like, said mechanism comprising a frame, a power driven shaft journaled for rotation in said frame, a drive wheel, overrunning clutch means coupling the drive wheel to said shaft, an epicyclic train including a driving gear carried by the drive shaft and a pair of driven gears in meshing engagement with said driving gear, one of said driven gears being secured to the drive wheel for common rotation therewith, the other of said driven gears being rotatable on the axis of said drive shaft, and mechanism for periodically locking said other driven gear against rotation for predetermined intervals and releasing the same, whereby the drive wheel is rotated by said one of the driven gears when said other driven gear is locked against rotation, said drive wheel being driven by the drive shaft through said overrunning clutch means responsive to release of said other driven gear, said mechanism for locking said other driven gear comprising a stop element and an abutment element one mounted on said other gear and the other on said frame, yielding means biasing one of said elements toward engagement

11

with the other thereof, and means for periodically moving said one of the elements away from operative engagement with the other thereof against bias of said yielding means.
